UNITED STATES PATENT OFFICE

168,290

COMBINATION LAMP AND DISPLAY DEVICE

Artus D. De Lano, Battle Creek, Mich.

Application September 17, 1951, Serial No. 16,670

Term of patent 14 years

(Cl. D48—20)

To all whom it may concern:

Be it known that I, Artus D. De Lano, a citizen of the United States, residing at Battle Creek, Michigan, have invented a new, original, and ornamental Design for a Combination Lamp and Display Device, of which the following is a specification, reference being had to the accompanying drawing, forming a part hereof.

Figure 1 is a front perspective view of a combination lamp and display device, showing my new design.

Figure 2 is a rear perspective view thereof.

Figure 3 is a front elevational view.

I claim:

The ornamental design for a combination lamp and display device, substantially as shown.

ARTUS D. DE LANO.
